CHARLES A. PIENKOWSKY, OF CHICAGO, ILLINOIS, ASSIGNOR TO THE ANTHONY SHIELD COMPANY, OF CHICAGO, ILLINOIS, A CORPORATION.

DRESS-SHIELD.

SPECIFICATION forming part of Letters Patent No. 754,284, dated March 8, 1904.

Application filed February 26, 1903. Serial No. 145,103. (No model.)

To all whom it may concern:

Be it known that I, CHARLES A. PIENKOWSKY, a citizen of the United States of America, and a resident of Chicago, Cook county, Illinois, have 5 invented a certain new and useful Improvement in Dress-Shields, of which the following is a specification.

My invention contemplates an improved 10 ventilating dress-shield composed of an outer layer of porous-mesh ventilating-cloth, a lining of fine nainsook, muslin, or the like and an interlining of odorless and impervious tissue—such, for example, as rubber, gutta-percha, or fish-bladder. With this construction 15 the shield not only is of a thoroughly waterproof character, but is also of such nature as to permit a free and beneficial circulation of the air. The nature and advantages of my invention will, however, hereinafter 20 more fully appear.

In the accompanying drawings, Figure 1 is a perspective of my improved dress-shield. Fig. 2 is a vertical section of the same. Fig. 25 3 is a side elevation showing a part of the outer mesh or gauze broken away for the purpose of exposing a portion of the tissue interlining and also showing a portion of the said interlining broken away for the purpose of showing the backing or lining proper.

As thus illustrated, the dress-shield comprises, preferably, two crescent-like pieces of 30 porous-mesh ventilating-cloth sewed or otherwise united at their concave edges, so as to provide the shield with the outer layer A of reticulated cloth having coarse openings or meshes. The backing or lining B of the shield can be of any suitable or desired material—such, for example, as fine nainsook, muslin, or other like material. This backing or lining 35 proper can also be composed of two crescent-like pieces of cloth sewed together or otherwise united at their concave edges. The intermediate layer or interlining C consists, preferably, of an odorless and impervious or 40 waterproof tissue—such, for example, as rubber, gutta-percha, or fish-bladder. In practice I find that a thin and more or less transparent or translucent tissue of this character 45

gives very good results, although it is obvious that there are various vegetable compounds or substances which may be employed in place of the materials mentioned and without departing from the spirit of my invention. Preferably and as is the case with the lining and the outer layer of porous-mesh cloth the 50 interlining of odorless and impervious tissue can be formed from two crescent-like pieces of tissue united at their concave edges. Preferably and as illustrated the three materials are not connected or united at the upper concave edge portion of the shield. The materials thus combined and arranged for preventing perspiration from reaching the outer cloth and for at the same time insuring a free and agreeable circulation of the air between the 55 shield and the body of the wearer may be united and bound up at their edges in any suitable manner—as, for example, by means of the edging or binding D. Thus it will be seen that my improved dress-shield is of a 60 three-ply character, the outer layers consisting of a reticulated or coarse-mesh fabric on one side and a more finely-woven cloth or fabric on the other side and the intermediate 65 ply or layer consisting of a thin, odorless, and absolutely waterproof tissue. This renders 70 the shield very flexible and light and comfortable, as well as thoroughly waterproof, and, as previously explained, has the further advantage of insuring the free circulation of the 75 air between the shield and the body of the wearer, and by the term "tissue" I mean a material like pure rubber, gutta-percha, or other like composition as distinguished from a woven cloth or fabric. By "odorless" I 80 mean a tissue which is either odorless or practically odorless or without an offensive odor.

What I claim as my invention is—

A dress-shield, comprising outer layers of cloth and an intermediate layer of thin waterproof tissue, one layer of cloth serving as a lining and consisting of closely-woven fabric, the waterproof tissue serving as a loose interlining between the two layers of cloth, the layer of cloth which goes next to the body 90 being coarsely woven and consisting of a por-

ous-mesh ventilating fabric, and all three layers, to wit, the layer of closely-woven cloth, the layer of porous-mesh ventilating fabric, and the intermediate layer of thin waterproof 5 tissue, being suitably bound together at the edges of the shield, substantially as shown and described.

Signed by me at Chicago, Cook county, Illinois, this 9th day of February, 1903.

CHARLES A. PIENKOWSKY.
